UNITED STATES PATENT OFFICE.

ARTHUR W. CHASE, OF NEW YORK, N. Y.

ROASTING-FURNACE.

No. 828,393.

Specification of Letters Patent.

Patented June 12, 1906.

Application filed July 1, 1903. Serial No. 163,919.

To all whom it may concern:

Be it known that I, ARTHUR W. CHASE, a citizen of the United States, residing at New York, in the county of New York and State 5 of New York, have invented certain new and useful Improvements in Roasting-Furnaces; and I do hereby declare the following to be a full, clear, and exact description of the invention, such as will enable others skilled in the 10 art to which it appertains to make and use the same.

My invention relates to improvements in roasting-furnaces, although it may also be used as a drying, chloridizing, and calcining 15 furnace as well.

The objects of my invention are to produce a furnace of greater efficiency than the furnace now in common use for roasting purposes, one that may be operated at a lower 20 cost and at a minimum expense for repairs.

Further objects are to produce a furnace in which the ore may be roasted to a "dead roast" or to a roast sufficient for smelting purposes, as may be desired, one that may be 25 used either as a muffle-furnace or a reverberatory furnace with slight changes in construction, and one that will efficiently roast every variety of ores.

With these objects in view my invention 30 consists in the construction and combinations of parts, as hereinafter described and claimed.

In the accompanying drawings, Figure 1 is a longitudinal section of my improved furnace, parts being removed. Fig. 2 is an end view, partly in cross-section, of two of my furnaces built side by side. Fig. 3 is a side view of my improved furnace, a part being shown in cross-section to show the construction 40 of the flues. Fig. 4 is a horizontal section taken on the line 4-4 of Fig. 2. Fig. 5 is a horizontal section of two of my furnaces built side by side, the section of one furnace being taken on the line A-A, Fig. 1, and the 45 section of the other furnace being taken on the line B-B of the same figure. Fig. 6 is a vertical section, on an enlarged scale, of the feeding part of my device, which may also be used as a drier. This figure is taken looking 50 from the opposite side of said feeder from what is shown in Fig. 1, and Fig. 7 is an end view of two of my furnaces built side by side and showing in dotted lines the means for driving the conveyers and the supporting- 55 frame for the masonry structure.

My improved furnace is composed of units,

each unit being a complete furnace in itself, although for convenience I usually build at least two of these furnaces side by side, making use of one chimney for both furnaces. I 60 do not restrict myself to this arrangement, however, as my furnace can be built as large as desired by combining any number of units together arranged side by side.

a represents a hopper of metal which is 65 supported, by means of braces *b*, directly upon the brickwork of the furnace. This hopper delivers into the top of the throat *c* of the combined feeder and drier, an iron collar *d* being preferably used at the point where 70 the hopper and the throat meet. The throat *c* delivers into a cylindrical chamber *e*, which is provided with a discharge throat or pipe *f*. The parts *c*, *e*, and *f* are made of a single piece of cast-iron, insuring great strength and rigidity. The ends of the cylindrical chamber *e* are closed by end pieces *g* and *h*, being secured thereto by bolts (not shown) or in any other suitable way. These end pieces *g* and *h* are cast in a single piece, as shown in Fig. 6, 80 and are perforated for the passage of the conveyer-shaft. They are each provided with cylindrical portions *i* and *j* and terminate in flanges *k* and *l* and are provided with braced bases *m* and *n*, which rest upon the top brick-work of the furnace. Within the cylindrical portions *i* and *j* is placed a filling of asbestos, mineral wool, or other suitable heat-resisting and dust-catching material. *o* and *p* represent end pieces for the purpose of holding the 85 packing in place, these being perforated for the passage of the conveyer-shaft. These end pieces may be extended, as shown at *q* in Fig. 6, for the sake of giving an additional extended bearing to the conveyer-shaft, or 90 they may be simple plates, as shown on the left of Fig. 6. They are secured to the parts *g* and *h* by bolts (not shown) or in any other suitable way.

Within the chamber *e* is a conveyer consisting of a shaft *r*, upon which is mounted a spiral conveyer *s*. This spiral conveyer is made up of sections, as shown in Fig. 6, any one of which may be easily removed for repairs. The conveyer-shaft *r* is hollow and is 100 cooled by water passing through it, the water being delivered at one end thereof and passing out at the other, as clearly shown in Fig. 1. The shaft *r* is provided with suitable stuffing-boxes *u*, one at each end, and screw-threaded projections *v* are provided, to which 105 flexible pipes *w* and *x* (see Fig. 1) may be

screwed. The whole feeding device is located within the brick arch *t*, (see Fig. 2,) resting on the top of the furnace. The discharge-pipe *f* passes down into a vertically-arranged pipe *y*, which delivers into the top of the upper roasting-trough *z*.

The pipe *y*, as well as the roasting-troughs, is made of carefully-selected and prepared fire-clay. Said pipe is provided at its upper end with a projecting lip *l*, which enters into a recess in the end wall of the furnace and also rests upon the brick arch *2*, which is sprung across between the side walls of the furnace. The lower end of the pipe *y* fits into a perforated fire-clay plate *3*, which is provided with a lip *4*, which surrounds the pipe *y* on three sides. The plate *3* rests upon and is supported by the trough *z*. The trough *z*, as well as the other roasting-troughs, is substantially but not exactly U-shaped in cross-section—that is, it has a circular bottom; but the sides thereof are not vertical, but are splayed outwardly, thereby enabling the operator by raising any one screw conveyer by means of the adjustable bearings to give the screw greater clearance from the bottom and sides of the trough should defects in the form of the trough due to defective manufacturing cause the screw to bind.

Within the trough *z* is a spiral conveyer *6*, carried on the hollow shaft which is provided with stuffing-boxes and cooled by a current of water flowing through said shaft, as has already been described in connection with the conveyer-shaft of the feeder. All four of the conveyer-shafts are of similar construction and, together with the feeder-shaft, are supported in bearings carried on independent supports *7* and *8*, arranged outside of the furnace, so as to be substantially free from the expansion and contraction that would ensue if they were directly attached to the walls of the furnace. In Fig. 6 is shown one form of a dust-excluding bearing, which has already been described; but I prefer to use in addition to said bearing a second bearing *9* outside of the main bearing and preferably slightly smaller, which bearing is filled with waste *10*, adapted to be saturated with oil. In Fig. 1 all the shafts are shown as provided with this double bearing. The ore-roasting troughs are made of carefully-selected fire-clay, and the entire interior is made of carefully-selected fire-brick and fire-clay forms. The outer walls may be either plain brick or fire-brick, as preferred.

Below the series of roasting-troughs which are arranged in vertical series one above the other is a shelf *14*, which separates the fire-box from the roasting-troughs. A similar shelf *15* is provided above the top roasting-troughs *z*, and by means of these shelves the fire and products of combustion are kept entirely apart from the roasting-troughs, thus

producing a muffle-furnace. The fire and products of combustion therefrom pass up through the flues *16* and *17*, located at opposite corners of the front of the furnace. They then pass over the shelf *15* through the passage *18* and out through the chimney *19*.

The passage *20* (shown in Fig. 1) is a passage connecting the top passage or flue of one furnace with that of a similar furnace next in line and may be closed by a damper or bricked up when it is desired to cut out one of the unit furnaces for the purpose of repairs, for example. On the shelf *14* rest fire-clay blocks *21* and *22*, which support fire-clay arches *23*, made of fire-clay and on which the lowest roasting-trough *13* rests. On the braces *23* are fire-clay blocks *24* and *25*, which support a series of fire-clay arches *26*, which support the roasting-trough *12*, and this construction is continued all the way up the furnace.

The spiral conveyers in the various roasting-troughs are revolved in opposite directions successively, so that the ore is fed forward through one, back through the next lower trough, forward through the next lower trough, and so on. At the end of each trough are discharge-pipes *27*, *28*, *29*, and *30* made of fire-clay. All of these except the lowest one are similar in construction and each consists of a pipe provided with an outwardly-projecting lip entering a recess in the wall of the furnace and being cut away above to fit around the trough just above it and being cut away below to fit upon a ledge in the supporting-plates *31*, *32*, and *33*, which rest upon the troughs *11*, *12*, and *13*, respectively.

Below the shelf *14* is the fire-box *34*, provided with a grate *35* and a charging-door *36*. Beneath the grate *35* is an ash-pit *37*, provided with a discharging-door *38*. Adjacent to the grate *35* is an inclined floor *39*, and this floor or plate *39* and the bottom of the ash-pit are made of fire-clay, though they may be made of other material in special cases. The bottom of the ash-pit and the plate *39* are supported in the side walls of the furnace, and the bottom of the furnace *40* rests upon a concrete foundation *41*, which affords a firm and stable base to the whole structure. A short distance above the bottom *40* of the furnace is an iron plate *42*, separated from the bottom and one end of the furnace by a short space. *43* represents an air-inlet and opening which may be closed by the door *44*. From beneath the plate run a series of flues arranged in pairs on either side of the roasting-troughs. The paired flues *45*, *46*, and *47* deliver air to the lowest trough *13*. The paired flues *48*, *49*, and *50* deliver air above the roasting-trough *11*, and the paired flues *51* and *52* deliver air above the roasting-trough *z*. Of course it is understood that paired flues are provided for each of said roasting-troughs, but to avoid confusion

some of these flues have been omitted from Fig. 1.

The roasting-troughs are open at the top and circular at the bottom, but are provided with relatively high sides. In an ordinary furnace they are preferably made in sections, as shown in Fig. 1, for convenience and economy in repairing a furnace if any one of said troughs should happen to become cracked or broken.

Peep-holes are provided at various places in the sides of the furnace. One of these is shown at 53 in Fig. 2 and is adapted to be closed by a brick 54. These peep-holes are 15 preferably arranged so that each trough may be separately inspected—that is to say, peep-holes are provided just above each trough and just above the shelf 15.

The furnace thus far described is a muffle-furnace; but this furnace may be easily converted into a reverberatory furnace or one in which the flame and products of combustion can impinge directly upon the roasting-troughs and the ore carried thereby simply 25 by taking out the shelves 14 and 15 and closing up the flues 16 and 17. The flame and products of combustion from the fire-box will then rise directly around the roasting-troughs and pass out through the chimney 19.

30 Any desired means of heat may be used in the fire-box, whether wood, coal, or gas. In many instances after the ore has once become hot the heat generated by the combustion of the ore itself is sufficient to maintain the 35 roasting operation until it has been completed.

In the type of furnace shown in Fig. 1 the gases evolved from the roasted ore for the purpose of making sulfuric acid are shown as 40 passing out through discharge-pipe 55, which is located underneath the lowest trough 13. It should be noted that the space beneath the arch *t* is subjected to the action of the hot gases evolved from the roasted ore, inasmuch as said gases can pass freely through the pipe *y* up into the space beneath said arch. These hot gases, which play around the tube *e* and the pipes *c* and *f*, heat them to a considerable degree, thus rendering the 45 pipe *e* a drier. The conveyer *s* prevents any appreciable amount of said gases from escaping up through the pipe *c* out through the open hopper *a*, and this is especially the case when as is usual in actual operation the pipe 55 *c* is filled with ore. The hot gases from the roasted ore come up through the pipe *y* and surround the tube *e* and heat it, thereby becoming cool when they fall back through the pipe *y* into the main portion of the furnace.

60 In muffle-roasting, generally speaking, the gases arising from the burning or chemical changes in the ore pass out through the pipe *y* and over and around the feeding and drying device and thence to the chambers or flues through an opening back of the heating

device through a passage, (not shown on the drawings,) thereby utilizing the heat of these gases to dry and heat the incoming ore. The drying-chamber thus becomes a very efficient dust-chamber.

70 It is important that the conveyer-shafts which pass through the roasting-troughs should not become warped or bent by the heating and cooling of the furnace. This is accomplished, as has already been described, by having these shafts water-cooled and by having the bearings therefor mounted in supports entirely separated from the furnace proper.

75 The ends of the furnace are provided with openings which are closed by plates 79. These plates have circular openings cut in them a little larger than the conveyer-shafts. Angle-irons 56 and 57 are secured to these plates 79 and to the end of the furnace by 80 bolts 80, which pass through said plates and into the wall of the furnace. Between these angle-irons and the side of the furnace separate plates, such as 58, 59, and 60, are secured, and these plates are cut away at their meeting edges for the passage of the conveyer-shaft—that is to say, each of the plates which fit around the conveyer-shafts are made in two sections which are adjustably secured together by plates, such as 61, secured by bolts 81, the holes through which said bolts 81 pass being larger than the bolts themselves, so that an exact adjustment may be obtained. The stuffing-boxes pass into the plates 61. In this way the conveyer-shafts are practically entirely independent of the closing-plates, which are free to expand or contract under the heating and cooling of the furnace. This arrangement of plates of course occurs on both ends of the furnace.

85 Tie-bolts such as 75, 76, and 78 pass through the walls of the furnace. The supporting-frame for the driving-gear 63, 64, 65, 66, 67, 68, and 69 is shown in Fig. 7.

90 The conveyer-shafts in the various roasting-troughs are arranged to travel at different rates of speed, increasing from the top downward, the conveyer in the top roasting-trough moving the slowest, while the conveyer in the lowest roasting-trough moves the fastest. This is desirable in order to prevent any possible clogging of the ore in the roasting-trough, and is especially desirable in order to lessen the depth of ore in the successive troughs, and thereby increase the 95 roasting-surfaces exposed to action. This is accomplished by having the sprockets upon the conveyer-shaft of different sizes, and in Fig. 7 are shown in dotted lines sprocket-drives for accomplishing this result.

100 While I have thus described my invention, I do not wish to be limited to the exact details shown and described, inasmuch as many of them might be varied without departing from the spirit of my invention; but

What I claim as new, and desire to secure by Letters Patent of the United States, is—

1. In a roasting-furnace, the combination of end walls provided with openings, bridge-walls, a series of substantially U-shaped troughs supported within said end walls, conveyers in said troughs, means for driving said conveyers, a plate provided with circular openings adapted to fit around the openings in the end walls, said plate being provided with slots and removable plates each made in two sections fitting around the conveyer-shafts and adapted to close the openings in the end walls, said plates being adjustably secured to the first-named plate, substantially as described.

2. In a roasting-furnace, the combination of the furnace proper, a metallic hopper supported on said furnace, a combined feeder and drier provided with flange resting on said furnace, a conveyer in said feeder and drier, a water-cooled shaft for said conveyer, and gas-check devices, said hopper and the ore contained therein being supported directly upon the masonry walls of the furnace, said iron feeder and drier being supported directly upon the furnace, and said shaft and conveyer being supported upon outside bearings, substantially as described.

3. In a roasting-furnace, the combination of roasting-troughs arranged one above the other, conveyers in said troughs, and removable shelves whereby said furnace may be used either as a muffle-furnace or as a reverberatory furnace, substantially as described.

4. In a roasting-furnace, the combination of end walls, side walls, roasting-troughs supported between said walls, removable shelves located one above said roasting-troughs and one below the same, thereby shielding said troughs from direct contact with the heat-supplying means, and means for delivering air to said roasting-troughs, substantially as described.

5. In a roasting-furnace, the combination of end walls, side walls, roasting-troughs secured between said walls, a fire-box, removable shelves, one located above said roasting-troughs and one below the same, means for conveying the flame and products of combustion from said fire-box around said roasting-troughs, and means for supplying air to said troughs, substantially as described.

6. In a roasting-furnace, the combination of end walls, side walls, roasting-troughs supported between said walls, a fire-box, removable shelves above and below said troughs, means for supplying air to said roasting-troughs, and a combined feeder and drier located above one of said roasting-troughs, substantially as described.

7. In a roasting-furnace, the combination of end walls, side walls, roasting-troughs therein, a conveyer in each of said troughs, shelves located one above said troughs and the other below the same thereby shielding said troughs from the direct action of the heating means, a combined feeder and drier for said troughs, said feeder and drier being shielded from the direct action of the heating means but being exposed to the action of the heated gases evolved from the roasting ore, and means for carrying off said gases, substantially as described.

8. In a roasting-furnace, the combination of end walls, side walls, a fire-box, a shelf located directly above said fire-box, roasting-troughs located above said shelf, a conveyer in each of said roasting-troughs, discharge-pipes for said roasting-troughs, a shelf located above said roasting-troughs, said shelves serving to shield said roasting-troughs from the direct action of the heating means, means for delivering air to said roasting-troughs, and means for carrying the products of combustion from the fire-box around said troughs, substantially as described.

In testimony whereof I affix my signature in presence of two witnesses.

ARTHUR W. CHASE.
